[57] CLAIM

The ornamental design for a tissue box holder, as shown and
described.

DESCRIPTION

FIG. 1 is a top right front perspective view of a tissue box
holder showing our new design;

FIG. 2 is a right side elevational view thereof, the left side
elevational view being a mirror image;

FIG. 3 is a front elevational view thereof; the rear eleva-
tional view being a mirror image;

FIG. 4 is a top plan view thereof; and,

FIG. 5 is a bottom plan view thereof.
